ARTICLE DISPENSING SYSTEM

Peter Lincoln Law, Roseville, near Sydney, New South Wales, Australia, assignor to Communication Engineering Pty. Limited, Cammeray, near Sydney, New South Wales, Australia, a company incorporated under the laws of Australia

Application May 26, 1949, Serial No. 95,495
In Australia June 11, 1948

9 Claims. (Cl. 235—92)

1

The invention relates to article dispensing systems and more particularly to arrangements associated with conveying means carrying various kinds of articles for selective release, to control the release of said articles and to give price indications in accordance with the prices of said various kinds of articles.

Article dispensing systems are known in which articles are stored on or in conveying means so arranged in shelves, bins or the like that said conveying means are set in motion each time an article has to be dispensed. A complete system of this character, to which the present invention is applicable, is fully described in copending application Serial No. 643,945, filed January 28, 1946, of T. S. Skillman, the said application being incorporated by reference herein. In the system of said application, conveying means move the desired kind of article to a point of discharge where the article is then released from said conveying means. Said conveying means are started and stopped by the operation of clutches which connect and disconnect the conveying means with a common driving shaft and these clutches are individually controlled in accordance with the desired kinds of articles. Furthermore it has been proposed in said copending application to use these clutch magnets for the operation of a price indicator in such a way that contacts on the individual clutch magnets mark the price of the corresponding articles on a pricing frame which transfers this price marking to a pricing unit and from there to lamp indicators, registers or the like.

Difficulties, however, arise when, for example, a check has to be made of the pricing unit, as hitherto there has been no possibility of operating the pricing unit without discharging articles from the various bins. Furthermore, comparatively complicated circuits are necessary to operate the clutch magnets without the pricing unit for the reloading of bins.

According to the present invention these difficulties are overcome by an arrangement which permits an operation of the value indicating means, for example a price indicator, independent of the release of articles from the storage and releasing devices of the article dispensing system. This arrangement includes switching means which are operated by the selecting mechanism of the article dispensing system and in turn operate independently the releasing means for selected articles and the value indicating means.

2

According to another feature of the invention checking means are provided which by their operation interrupt the operating circuit for the releasing means, so that upon selection only the value of the selected article is indicated, but the article itself is not released from storage.

It is a further feature of the invention to operate the releasing means without operating the value indicating means to facilitate the reloading of the storage devices.

According to a further feature of the invention all releasing means are operated over a common circuit which is equipped with a spark quench device to suppress the sparking at the contact operating the releasing means. By using a common circuit only one spark quench device is necessary for all releasing means.

These and other features of the invention will be more apparent from the following description in conjunction with the drawings, which show one embodiment of the invention incorporated in an article dispensing system.

In the drawings

Fig. 1 shows in schematic form a selecting circuit for an article dispensing system.

Fig. 2 is a schematic diagram of the electrical equipment associated with the releasing devices of an article dispensing system.

Fig. 3 shows circuits for adding the prices of articles selected for release by the article dispensing system.

Fig. 4 is an example of a storage and releasing device which may be used in conjunction with the invention.

Fig. 5 shows how the Figures 1, 2 and 3 may be placed together to form a continuous circuit diagram.

Articles are selected for dispensing from the apparatus by pressing two of the keys K1 . . . K0 (Fig. 1) in succession, the combination depending on the code allotted to the article required. This results in the operation of a clutch relay such as 11CR (Fig. 2) which energises a clutch 11CL (Figs. 2 and 4), which in turn causes the article required to be released from storage. The released article strikes a trip contact 11TC which restores the circuits to their normal positions ready for selection of the next article.

Operation of a clutch relay completes circuits, to the pricing unit shown in Fig. 3, through a value determining device or pricing frame 30 (Fig. 2), which relates the connections between the clutch relays and the pricing unit to the amount to be charged for each article. The value determining device can be any form of jumpring ar-

angement which permits selective connections to be made between various groups of electrical conductors. The pricing unit adds the prices of the various articles dispensed to make up an order and indicates the total on an indicator 31 (Fig. 3). The pricing unit may be reset to zero by operation of the key FK (Fig. 3). A continuous total of the prices of all dispensed articles is recorded on register PTR (Fig. 3) and the total of any special group of transactions, e. g. articles dispensed by particular salesmen, may be recorded by completing a circuit for register PSR (Fig. 3).

To permit the prices of articles to be checked without releasing the articles from storage a key CH (Fig. 1) is provided which may be operated to disconnect clutches performing the dispensing of articles and to permit the prices of articles to be indicated and added in the pricing unit as the article codes are set up on the keys.

It is sometimes necessary to operate the article storage and releasing devices (for example as shown in Fig. 4 and described hereafter) without operating the article pricing equipment, as occurs, for example, in reloading a system in which articles are stored on conveyor belts. In this case the belt must be moved forward while articles are being loaded onto it. Such an arrangement is shown in Fig. 4, where the clutch 11CL operates through lever 54 to engage the gear wheels 52, one of which is fixed to a continuously rotating shaft 53. The other gear 52 is fixed to shaft 51 which also carries roller 50. The belt 38 on which articles 37 are stored passes around rollers 39 and 50 so that engagement of the clutch moves the belt until the first article topples off to be carried away on some form of conveyor 56. While toppling, the article strikes the member 55, thus operating the trip contact 11TC.

To reload the belt 38 a loading bar 57, which may be common to several belts, and which is supported by arms 58 pivoted at 59, is lowered to the position shown by the dotted lines. This prevents articles toppling off the front of these belts, which may now be driven forward while articles are loaded onto the back of them. A loading switch such as is shown in Figs. 2 and 4 by contacts ILS1 and ILS2 is associated with each loading bar 57 to condition the group of storage and releasing devices for the loading operation. These contacts are operated when the loading bar is in its lowered position and prepare circuits for the various clutches so that the associated storage and releasing devices may be operated by inserting a plug with a connection between the "tip" and "ring" conductors into the corresponding loading jacks 11LJ, 10LJ . . . (Fig. 2) to complete the circuit to the clutches 10CL, 11CL . . .

The operation of the circuits involved will now be described in detail:

To operate the apparatus for the release of an article from storage the digits of the code corresponding to the wanted article are transmitted to the apparatus by means of a set of ten keys K1 . . . K0, of which three are shown in Fig. 1.

Fig. 1 shows the circuit arrangement for selection of two-digit codes, thus giving a capacity of 100 articles, but this may be extended in size by using three or more digits in the selection. For two-digit codes there will be ten relays A-J associated with the keys K1-K0 and each relay has 11 contacts $a_1-a_{11}-j_1-j_{11}$. Only three of these relays are shown in Fig. 1 and on these some of the contacts are omitted for clearness. It will be appreciated, however, that the remaining re-

lays and contacts are connected in a similar manner to those shown in Fig. 1.

Assuming that an article corresponding to the code 11 is required, the key K1 will be pressed twice in succession. When the key is pressed the first time relays A and S operate in series from earth over key K1, contact m_1 , coil of relay A, coil of relay S, to battery. Relay A closes its contacts a_1 to a_{10} . Operated contacts a_1 to a_{10} 5 prepare circuits to ten clutch relays of which two are shown in Fig. 2 by 10CR and 11CR, but these circuits are not yet completed to earth. Operated contact a_{11} prepares a holding circuit for relay A. Relay S operates its contact s_1 which completes a circuit for relay N which in turn operates its contacts n_1 and n_2 . Operated contact n_1 prepares a circuit for relay M and operated contact n_2 completes the holding circuit for relay A from earth over operated contact n_2 , operated contact a_{11} , 15 relay A, to battery. Operated contact n_2 also completes a holding circuit for relay N from earth, over operated contact n_2 , contact pc_3 , relay N, to battery. While the key K1 is held pressed relays A, S and N remain operated. 20 When the key K1 is released relays A and N remain operated over their holding circuits but relay S releases. Contact s_1 now completes a circuit for relay M from earth, over contact s_1 , operated contact n_1 , relay M, to battery. Relay M operates its contacts m_1 to m_{10} which disconnect the keys K1 . . . K0 from relays A to J 25 and connect them to the leads to the clutch relays.

When key K1 is again pressed for the selection of the second digit a circuit is completed for relay 11CR (Fig. 2) and relay PC (Fig. 1) in series. This circuit is from earth over key K1, operated contact m_1 , operated contact a_1 , lead 20 (Figs. 1 and 2), relay 11CR, contact ILS2, lead 22 (Figs. 2 and 1), contact ca_2 , relay PC, to battery. Relay PC operates its contacts pc_1 to pc_5 . Operated contact pc_1 breaks the circuit for slow-release relay T, which is normally operated, but this has no effect at this stage, since its only contact t_1 is shunted by contact ca_2 . Operated contact pc_2 prepares a circuit for the operation of the storage and releasing device which will be described below. Operated contact pc_3 opens the circuit for relay N, which releases, but operated contacts pc_4 and pc_5 maintain the holding circuits for relays A and M, which would otherwise be broken by the release of relay N. Relay 11CR (Fig. 2) closes its contacts $11cr_1$ to $11cr_5$. Operated contact $11cr_1$ closes a holding circuit from earth, over trip contact 11TC, relay 11CR, contact ILS2, lead 22 (Figs. 2 and 1), contact ca_2 , relay PC to battery. Thus, when the key K1 is released again, relays 11CR and PC remain operated. Operated contact $11cr_2$ (Fig. 2) closes a circuit for the clutch 11CL, which forms part of the storage and releasing device, from earth over clutch 11CL, loading jack 11LJ, operated contact $11cr_2$, lead 25 (Figs. 2 and 1) operated contact pc_2 , contact ca_1 to battery. Operated contacts $11cr_3$, $11cr_4$ and $11cr_5$ close circuits which will be described later.

The clutch 11CL operates as previously described to release an article from the storage and releasing device, and the released article momentarily opens the trip contact 11TC. This breaks the circuit for relays 11CR and PC which release. However, relay PC is so designed that it will release before relay 11CR, so that the circuit to clutch 11CL is broken first at contact pc_2 . The spark quench circuit SQ (Fig. 1) absorbs the cur-

rent induced in clutch CL when the circuit is broken. Thus it will be seen that only one spark quench circuit SQ is required instead of needing one for each clutch if the contact pc2 did not break before contact 11cr2 . The release of relay PC breaks the holding circuit for relays A and M which release, thus restoring the circuit to normal ready for the next selection.

When relay 11CR (Fig. 2) operates, operated contacts 11cr3 , 11cr4 and 11cr5 complete circuits through the pricing frame 30 to the pricing unit shown in Fig. 3. In the preferred arrangement this pricing frame has a number of sets of horizontal conductors 33 and 34 (Fig. 2), one conductor in each set being associated with the contacts of each clutch relay. As many sets of horizontal conductors will be required as there are denominations in the prices of articles to be dispensed. In Fig. 2 two sets of horizontal conductors are shown, associated with two of the contacts on each clutch relay, and representing shillings and pence. An extra contact is shown on each clutch relay which would be used if a third denomination (either pounds or half-pence) were required.

Associated with each set of horizontal conductors, but insulated therefrom, is a set of vertical conductors 35 and 36, each set having one conductor for each value in the denomination it represents. In Fig. 2 there would be twelve conductors 36, representing 0 to 11 pence and up to 20 conductors 35 representing 0 to 19 shillings. These vertical conductors are connected through cables 28 and 29 to relays in the pricing unit shown in Fig. 3. The conductor representing one penny will be connected to relay 1P , the conductor representing eleven pence will be connected to relay 11P and so on.

Connections may be made between each horizontal conductor and a vertical conductor at their intersection to connect the two conductors required. Thus an earth applied through a contact of a clutch relay may be made to operate any required relay in the pricing unit, corresponding to the price to be charged for the articles associated with this particular clutch relay.

In the pricing unit (Fig. 3) the apparatus for adding the pence is shown in detail, but the apparatus for adding the shillings, which is almost identical to that for the pence, is represented by the rectangle 37, which will be referred to as being similar to the pence adding unit, except for the details indicated in the rectangle 37, concerning the carry-over from pence to shillings denominations.

Suppose the price of each article released by clutch 11CL was eleven pence. When relay 11CR operates it completes a circuit for relay 11P (Fig. 3) from earth over operated contact 11cr4 (Fig. 2), horizontal bar 34, the vertical bar 36 corresponding to eleven pence, cable 28 (Figs. 2 and 3), coil of relay 11P to battery. Relay 11P operates and closes its contacts 11p1 and 11p2 . Operated contact 11p1 prepares a circuit for relay 11CP and operated contact 11p2 completes a holding circuit for relay 11P from earth, over contact 1cpa1 , relay PP, operated contact 11p2 , coil of relay 11P , to battery.

Relay PP also operates over this circuit and closes its contacts pp1 and pp2 . Operated contact pp1 prepares a holding circuit for relays 11CP and 11CPA , and operated contact pp2 closes a circuit for relay PA from earth, over contact oc2 , wiper and arc pm6 , contact pm2 , contact

1cpa2 , operated contact pp2 , relay PA to battery.

Relay PA operates its contacts pa1 to pa4 . Operated contact pa2 completes the circuit for relay 11CP from earth over operated contact pa2 , operated contact 11p1 , contact 1cpa1 , relay 11CP , to battery. Relay 11CP operates and closes its contact 11cp1 which applies earth over operated contact pp1 , operated contact 11cp1 to the coil of relay 11CPA , but this relay already has earth applied to the other end of its coil and so will not operate. Operated contact pa3 closes a circuit from earth, over operated contact pa3 , contact cb1 , register PTR, to battery. PTR is a counting register which indicates the total number of pence counted by the apparatus. This register operates over this circuit and at this stage increases its indication by one penny. Operated contact pa4 closes a similar circuit for the register PSR. This register is similar to PTR but will operate only if earth is applied to lead 40. This circuit may be completed through a contact operated whenever required, for example, to register the sales of a particular class of article or to register sales made by a particular salesman. There may be several registers connected in a similar manner to PSR, the circuit of each being selectively earthed when it is required to operate that register. Operated contact pa1 closes a circuit from earth over operated contact pa1 , magnet PM, to battery.

Magnet PM is the driving magnet for a rotary switch having three banks of contacts with wipers represented by pm4 , pm5 and pm6 . These wipers step from contact to contact each time magnet PM releases, and when they leave the last contacts of the banks, the other ends of the wipers make contact again with the first contacts in the banks. This type of switch is well known in the telephone art. The switch used here is shown as having thirteen contacts on each bank, but it is well known that arrangements can be made to use switches with a greater number of contacts, stepping automatically over those which are not required. When the magnet PM operates, it opens its contacts pm1 to pm3 . Contacts pm1 and pm3 have no function at this stage but contact pm2 breaks the circuit for relay PA, which releases, thus interrupting at contacts pa3 and pa4 the circuits for the registers PTR and PSR. Contact pa2 removes the earth from the junction of the coils of relays 11CP and 11CPA and these two relays operate in series from earth, over operated contact pp1 , operated contact 11cp1 , relay 11CPA , relay 11CP , to battery. Relay 11CPA operates its contact 11cpa1 , which prepares a circuit for relay 10CP . Contact pa1 releases magnet PM.

The release of magnet PM steps the wipers pm4 , pm5 and pm6 on to the next contacts. Wiper pm4 applies earth to a lamp in an indicator 31 so that the next lamp on this indicator will be lighted when the switch steps on. Contact pm2 recloses the circuit for relay PA which re-operates. The contacts of relay PA fulfil the same functions as before, except that contact pa2 now causes the operation of relay 10CP from earth, over operated contact pa2 , operated contact 11p1 , operated contact 11cpa1 , contact 10cpa1 , relay 10CP , to battery.

As relay PA operates magnet PM and magnet PM releases relay PA, this sequence will continue, causing registers PTR and PSR to step on, wipers pm4 , pm5 and pm6 to step on, and the various relays 10CP , 10CPA , 9CP , 9CPA etc. to operate at each step. Relays from 2CP , 2CPA to 9CP ,

9CPA in this chain have not been shown in Fig. 3 but it will be readily understood that their operation is the same as for those shown. After eleven steps have been made relay 1CPA operates in series with relay 1CP and operates its contacts 1cpa1 and 1cpa2. Operated contact 1cpa2 prevents relay PA from re-operating and operated contact 1cpa1 opens the holding circuit for relays 11P and PP which release. Contact pp1 releases all the relays 1CP-11CP and 1CPA-11CPA, while contact pp2 prevents the re-operation of relay PA.

Thus the operation of clutch relay 11CR in Fig. 2 has caused the addition of eleven pence into the register PTR and into register PSR, if this is in circuit, and stepped the wiper pm4 around eleven steps, to make it indicate eleven pence more than before. If the connection on the pricing frame 30 had between the bar 34 and the vertical bar representing tenpence, the relay 10P would have operated instead of relay 11P and in turn would have operated relay 10CP, thus only ten steps would have been made before the stepping was terminated by operation of relay 1CPA.

A similar process takes place in the shillings adding unit 37, initiated by a circuit from earth, over operated contact 11cr3 (Fig. 2), a vertical bar 35, cable 29 (Figs. 2 and 3) to the appropriate relay in the shillings adding unit 37. This unit contains relays, registers and switches, similar to the pence adding unit, and therefore is not described in detail. A few elements of the circuit are shown in 37, however, where these differ from the pence adding unit, for accepting amounts of one shilling carried forward from the pence adding unit, as will now be described.

In the foregoing description of the adding process it was stated that the switch wipers would make eleven steps, so adding eleven pence. However, the switch may be in such a position that the addition will entail carrying forward one shilling into the shillings adding unit. For example, if fourpence was already recorded, the addition of elevenpence would result in an amount of one shilling and threepence, the shilling to be transferred to the shillings adding unit and the threepence to be indicated on the lamp indicator 31.

Referring again to Fig. 3, it will be seen that the circuit of relay PA includes the wiper pm6 and twelve contacts of its bank. When the switch steps onto the thirteenth contact, however, there is no circuit to relay PA and so the stepping circuit is broken. In this position the switch has reached twelve pence and one shilling must be added in the shillings adding unit and then magnet PM may step the switch onto the zero position to complete the adding of pence.

In the thirteenth position of the switch, earth is applied through contact oc2, wiper pm6 and its thirteenth contact, contact pm3, relay CC, to battery. Relay CC operated its contacts cc1 to cc3. Operated contact cc1 closes a circuit for switch magnet PM, over contact pa1, operated contact cc1, switch magnet PM, to battery. Thus the switch is prepared to step onto the zero position, but cannot do so until the circuit is again broken by relay CC. Referring now to the shillings adding unit 37, relay SA is shown which fulfils the same function as relay PA in the pence adding unit. Magnet SM fulfils a similar function as magnet PM in the pence adding unit and the number of shillings added will be shown on an indicator similar to 31. The relay SA nor-

mally operates over contact cc3 of the relay CC but when relay CC operates, this circuit is broken. If relay SA is operated at that time, however, the circuit is still completed through contact sa2, thus permitting relay SA to complete its cycle of operation but not to re-operate once it releases. With relay SA released a circuit is completed from earth, over contact sa1, operated contact cc2, magnet SM, to battery. Thus magnet SM operates and prepares to step its wipers on. Magnet SM operates its contact sm1, and as magnet PM has also opened its contact pm3, relay CC releases. Contact cc2 releases magnet SM which steps on one shilling. Contact cc3 restores the circuit for relay SA which restarts the counting process. Contact cc1 releases magnet PM, which steps its wipers onto the first position, restoring the counting circuit to relay PA, and indicating 0 pence on indicator 31. This unit now counts any remaining pence.

By these means as each article is released from the releasing devices its price is automatically determined and added into the adding units, which show a progressive total of the articles sold. When an order of several articles has been assembled and the price noted, it is necessary to restore the indicator 31 and the corresponding shillings indicator to zero ready for the next order. This is accomplished by operating key FK 30 (Fig. 3) which operates relay OC. The contact oc1 closes a circuit from earth, over operated contact oc1, wiper pm5 and contacts 2 to 13 of its back, contact pm1, magnet PM to battery. The magnet PM will thus operate, break its own circuit at contact pm1, release and step on, remake its circuit, and so on until it reaches the first contact, where the circuit is broken at wiper pm5. The contact oc2 disables relay CC during this operation, to prevent misoperation of the carry forward circuit. Other contacts of relay OC perform similar functions for the shilling adding unit 37.

Although as described only two denominations are handled by this pricing unit, the third set of contacts 11cr5 etc. could be wired through similar equipment to price in half-pence or in pounds, and carry forward circuits similar to the one described could be used to transfer amounts to the next higher denomination. Similarly, there is no need for the apparatus to be limited to sterling currency, any other currency may be used with only slight variations in the details of the circuits.

The apparatus in Fig. 3 is concerned with adding together the prices of various articles in an order. To indicate the price of each article as it is released another indicator may be provided which responds to the relays 1P-11P and indicates each price as it is transmitted to the adding units.

It is often desirable to be able to make use of the pricing facilities of the apparatus without releasing articles from storage. This may be done to permit the price being charged for any article to be checked, or to total the values of a number of articles which are not required to be assembled at the time, or which have been assembled manually, or to check the addition of the items of a previous order.

To provide this feature a key CH (Fig. 1) is fitted, which may be operated to prevent the operation of the clutches (11CL etc.). Operation of key CH operates relay CA with its contacts ca1 to ca3. Operated contact ca1 breaks the circuit to the clutches, and operated contact ca2

breaks one of the two paths between relay PC and the particular clutch relay (11CR etc.) that is operated. The operated contact *ca3* operates relay CB (Fig. 3) which breaks the circuits to the registers PTR and PSR. Instead of relay CB additional contacts of relay CA can be used for the same purpose.

When an article code is now transmitted to the apparatus by means of keys K1-K0 (Fig. 1), the circuit functions as previously described, except as explained hereunder:

When relay PC operates, no circuit is completed for the clutch as contact *ca1* is operated. As no article is released, the trip contact cannot be used to release the clutch relay and relay PC. To effect this release the circuit is broken at contact *t1* of relay T, which is a slow-release relay, released by contact *pc1*, so that a short time after relay PC operates its circuit is broken by contact *t1*, thus releasing also the clutch relay and the relays set up during the selection of the article code. The apparatus is then ready for selection of the next article code.

The operation of the clutch relay transmits the price to the pricing unit in the usual manner, and successive prices so transmitted will be added together. The operation of relay CB disables the registers PTR and PSR, so that they do not add the amounts into their total. Should it be preferred, however, one or more of these registers could be left in circuit to include the total of such amounts or a separate register could be brought into circuit by a make contact of relay CB to keep a separate record of these transactions.

At other times it becomes necessary to operate the storage and releasing devices without operating the selecting or pricing devices. For example, when it is necessary to load more articles into the device shown in Fig. 4, the loading bar 57 is lowered to prevent articles falling off the belt 38, which is then driven forward, sliding under any articles which abut the loading bar and carrying forward any articles loaded onto the back of the conveyor belt. The loading bar 57 may be common to a number of storage and releasing devices in the same horizontal row and the contacts operated by it will be included in the circuits of the storage and releasing devices associated with that loading bar. In Fig. 2 the storage and releasing devices associated with relay A of Fig. 1 are shown also associated with the loading bar contacts ILS1 and ILS2, but any other storage and releasing devices could be associated with that particular loading bar 57 and connected through the same contacts ILS1 and ILS2.

To load articles onto the device shown in Fig. 4 the loading bar 57 is first lowered into the position indicated by the dotted lines. This operates the contacts ILS1 and ILS2. Operated contact ILS2 breaks the circuit between relay PC (Fig. 1) and the relays 10CL-11CL etc. of the storage and releasing devices associated with this loading bar, thus preventing these devices from being operated by the keys. Operated contact ILS1 applies battery to the tip connections of the loading jacks 10LJ, 11LJ.

A plug having the tip and ring conductors connected together is now inserted in the jack 11LJ, thus completing a circuit from earth over clutch 11CL, loading jack 11LJ, loading bar switch ILS1, to battery. The clutch operates and draws the belt forward so that articles may be loaded on to the back of it and carried forward toward the loading bar 57 which prevents the articles from leaving the belt at this end.

The provision of a separate clutch relay CR for each bin enables the operation of the pricing unit PU and the clutch magnet CL independently from each other and furthermore simplifies the circuits and contact arrangements necessary to ensure a reliable working of the system.

By inserting a dummy plug in the jack LJ of a bin circuit the corresponding clutch magnet CL can be isolated to prevent the discharge of articles from this bin in case a fault has developed in the bin arrangement.

The foregoing description shows the invention by way of example only. Instead of price indications other value indications can be checked in the same manner. Modifications in the circuits as well as in the principle of working can be made without departing from the spirit of the invention.

I claim:

1. A value indicating and registering arrangement comprising: a set of contact members selectively operable in accordance with the designations of the kinds of articles to be valued; a selecting mechanism electrically connected with said contact members; switching means individual to each kind of article and electrical connections therefrom to said selecting mechanism, each of said switching means being selectively operable by the operation of said contact members in accordance with the designation of the corresponding kind of article; a locking circuit for each of said switching means; a timing device including relay means and electrical connections therefrom to said switching means and operable therewith to interrupt said locking circuits a predetermined time interval after the operation of any of said switching means; a jumpering frame including two groups of terminals, one group of terminals of said jumpering frame being electrically connected with said switching means; and value indicating and registering means and connections therefrom to the other group of terminals of said jumpering frame, the connections between the two groups of terminals of said jumpering frame being adjustable to alter the relationship of any of said switching means to said indicating and registering means.

2. A value indicating and registering arrangement comprising a set of contact members selectively operable in accordance with the designations of the various kinds of articles to be valued; switching means individual to each kind of article; a selecting mechanism common to and electrically connected with said switching means and further electrical connections from said common selecting mechanism to said set of contact members to selectively operate any of said switching means in accordance with the designation of a kind of article selected by said contact members; pre-settable value determining means to define the value of each kind of article, said value determining means being common to and electrically connected with said switching means to determine the value of each selected article; a timing device and electrical connections therefrom to said switching means and operable there-

with to release any operated switching means after a predetermined time interval; value indicating and registering means and electrical connections therefrom to said value determining means to indicate and record the value of each selected article; and means interposed in said electrical connections between said value determining means and said indicating and registering means and operable by said value determining

means and said switching means to relate each of said switching means to the particular indicating and registering means indicating the value of the corresponding kind of article.

3. In an article dispensing system a value indicating and registering arrangement including value indicating and registering means for the various kinds of articles to be dispensed; a set of contact members selectively operable in accordance with the designations of said various kinds of articles; switching means individual to each kind of article; a selecting mechanism common to and electrically connected with said switching means and further electrical connections from said selecting mechanism to said set of contact members to selectively operate any of said switching means in accordance with the designation of a kind of article selected by said contact members; a plurality of storage devices each carrying one of said kinds of articles for dispensing; releasing means individual to said storage devices and electrical connections from each of said switching means to a corresponding releasing means to effect the release of an article of the corresponding kind on the selection of said switching means; and pre-settable value determining means to define the value of each kind of article, said value determining means being common to and electrically connected with said switching means and said value indicating and registering means to determine the value of each selected article and to operate the particular value indicating and registering means indicating and registering the value of said articles.

4. In an article dispensing system for the dispensing of articles of various kinds a plurality of storage devices carrying articles to be dispensed and electrically operated releasing means associated therewith; pre-settable value determining means; value indicating and adding means and electrical connections therefrom to said value determining means; an article selecting mechanism common to said storage devices; and switching means individually associated with said releasing means and electrical connections from said selecting mechanism to said switching means for the selective operation thereof, said switching means having electrical contact means and electrical connections therefrom to corresponding releasing means for the selective release of articles from said storage devices and further electrical contact means and electrical connections therefrom to said value determining means to determine the value of each selected article and to indicate and add said value at said value indicating and adding means.

5. In an article dispensing system for the dispensing of articles of various kinds a plurality of storage devices carrying articles to be dispensed and electrically operated releasing means associated therewith; value indicating and adding means; an article selecting mechanism common to said storage devices; switching means individually associated with said releasing means, and electrical connections from said selecting mechanism to said switching means for the selective operation thereof, said switching means having electrical contact means and electrical connections therefrom to corresponding releasing means for the selective release of articles from said storage devices, and further electrical contact means associated with and operable by said switching means and electrical connections therefrom to said value indicating and adding means to indicate and add the value of each selected

article; and a loading switch and a jack interposed in the operating circuit of said releasing means, said jack being operable to disconnect said switching means from said releasing means and to connect said releasing means with said loading switch, said loading switch being operable to close a circuit for said releasing means and to interrupt the circuit for said switching means.

6. In an article dispensing system for the dispensing of articles of various kinds a plurality of storage devices carrying articles to be dispensed and electrically operated releasing means associated therewith; value indicating and adding means; an article selecting mechanism common to said storage devices; switching means individually associated with said releasing means, and electrical connections from said selecting mechanism to said switching means for the selective operation thereof, said switching means having electrical contact means and electrical connections therefrom to corresponding releasing means for the selective release of articles from said storage devices, and further electrical contact means associated with and operable by said switching means and electrical connections therefrom to said value indicating and adding means to indicate and add the value of each selected article; a loading switch and a jack interposed in the operating circuit of said releasing means, said jack being operable to disconnect said switching means from said releasing means and to connect said releasing means with said loading switch; a common lead for the operating circuits of a plurality of said switching means and electrical connections between said common lead and said loading switch, said loading switch being operable to close a circuit for said releasing means and to interrupt said common lead.

7. In an article dispensing system for the dispensing of articles of various kinds a plurality of storage devices carrying articles to be dispensed and electrically operated releasing means associated therewith; pre-settable value determining means; value indicating and adding means and electrical connections therefrom to said value determining means; an article selecting mechanism common to said storage devices; switching means individually associated with said releasing means and electrical connections from said selecting mechanism to said switching means for the selective operation thereof, said switching means having electrical contact means and electrical connections therefrom to said value determining means to determine the value of each selected article, and further contact means and electrical connections therefrom to said releasing means; a locking circuit for each of said switching means; and value checking means and electrical connections therefrom to said releasing means and said switching means, said value checking means upon actuation interrupting said locking circuits and the operating circuits of said releasing means.

8. In an article dispensing system for the dispensing of articles of various kinds a plurality of storage devices carrying articles to be dispensed and electrically operated releasing means associated therewith; pre-settable value determining means; value indicating and adding means and electrical connections therefrom to said value determining means; an article selecting mechanism common to said storage devices; switching relays individually associated with said releasing means and electrical connections from said selecting mechanism to said switching relays.

said switching relays having contact sets and electrical connections therefrom to said releasing means and said value determining means to independently operate said releasing means and said value indicating and adding means; a locking circuit for each of said switching relays; a timing device and electrical connections therefrom to said switching relays and operable therewith and a checking relay and contacts thereof interposed in the operating circuits of said releasing means and said locking circuits to interrupt said operating circuits on the operation of said checking relay and to render said timing device effective to interrupt said locking circuits after a predetermined time interval.

9. In an article dispensing system for the dispensing of articles of various kinds a plurality of storage devices carrying articles to be dispensed and electrically operated releasing means associated therewith; pre-settable value determining means; value indicating and adding means and electrical connections therefrom to said value determining means; value registering means and electrical connections therefrom to said value indicating and adding means to register amounts added in said adding means; an article selecting mechanism common to said storage devices; switching relays individually associated with said releasing means and electrical connections from said selecting mechanism to

5 said switching relays, said switching relays having contact sets and electrical connections therefrom to said releasing means and said value determining means to independently operate said releasing means and said value indicating and adding means; a locking circuit for each of said switching relays; a timing device and electrical connections therefrom to said switching relays and operable therewith to interrupt said locking circuits after a predetermined time interval; and 10 a checking relay and contacts thereof interposed in the operating circuits of said releasing means and said value registering means respectively to prevent the operation of said releasing means and 15 said value-registering means on operation of said checking relay.

PETER LINCOLN LAW.
